US0D1068476S

(12) **United States Design Patent** (10) **Patent No.:** **US D1,068,476 S**
(45) **Date of Patent:** **** Apr. 1, 2025**

(54) **CAP FOR AEROSOL GENERATING DEVICE**

(71) Applicant: **Philip Morris Products S.A.**,
Neuchâtel (CH)

(72) Inventor: **Alexander Farrow**, Pleasant Hill, CA
(US)

(73) Assignee: **Philip Morris Products S.A.**,
Neuchâtel (CH)

(**) Term: **15 Years**

(21) Appl. No.: **29/917,673**

(22) Filed: **Nov. 21, 2023**

Related U.S. Application Data

(62) Division of application No. 29/785,396, filed on May 25, 2021, now Pat. No. Des. 1,024,773.

(57) **CLAIM**

The ornamental design for a cap for aerosol generating device, as shown and described.

DESCRIPTION

FIG. 1 is a top perspective view of a cap for aerosol generating device showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof; and,

FIG. 8 is a bottom perspective view thereof.

The broken lines shown in the drawings depict portions of the cap for aerosol generating device that form no part of the claimed design.
